UNITED STATES PATENT OFFICE.

WILLIAM F. SMITH, OF SAN FRANCISCO, CALIFORNIA.

ELECTRICALLY-OPERATED TYPE-WRITER.

1,324,751.

Specification of Letters Patent.

Patented Dec. 9, 1919.

Application filed October 17, 1917. Serial No, 197,082.

To all whom it may concern:

Be it known that I, WILLIAM F. SMITH, a citizen of the United States, residing at the city and county of San Francisco and State 5 of California, have invented certain new and useful Improvements in Electrically-Operated Type-Writers, of which the following is a specification.

The hereinafter described invention relates to electrically controlled means for actuating a typewriter of standard construction, the objects thereof are to produce a quiet or silent actioned apparatus, the controlling parts of which shall be simple in 10 construction and efficient in operation; and one wherein the type of keys may be thrown into action without the heavy blow at the present time required to be given the key action in typewriters for throwing the type 15 key against the platen roll of the machine; to provide means to dispense with the levers now in common use and which produce the annoying click noise so common in typewriter machines, and to provide for the utilization of electric energy during the operation of the machine to take the place of the 20 present manual labor.

In the present invention, the platen roll, instead of being sent forward step by step 25 through the action of a coiled spring, is sent forward by the action of an armature actuated by magnets which are energized by the closing contact controlled by the movement of the finger keys, the said armature carrying a dog adapted for engagement with and advancing a dog-wheel one tooth at a 30 time, and, by so doing, imparting a step by step action to the platen roll. During the first portion of the downward movement of 35 either of the finger keys for the type-bars, there is closed a contact for producing the action just referred to, and a further downward movement of said finger keys makes a second contact which closes a circuit and 40 throws into action means for operating or throwing the type bars to cause the printing on the platen, and which type bars on a release of pressure from the finger keys immediately drop back to normal position.

In order to comprehend the invention, reference should be had to the accompanying 45 sheets of drawings, wherein,

Figure 1 is a top plan view of the typewriter, with certain parts thereof removed, 50 in order to more clearly show the working arrangements of one part with another.

Fig. 2 is a front elevation of the typewriter broken away, certain of the parts being removed.

Fig. 3 is a side elevation with the frame 60 of the machine partly broken away, said view illustrating certain of the finger keys and the contacts associated therewith and the magnets for controlling the operation of the armature for actuating the type bars, 65 the position of the type bars when raised being illustrated in dotted lines.

Fig. 4 is a detailed view of the mechanism for imparting a step by step movement to the platen for securing the proper letter 70 spacing.

Fig. 5 is a broken detailed view illustrating two of the finger keys and the separated contacts associated therewith.

Fig. 6 is an enlarged detail of the step 75 actuating mechanism disclosed by Fig. 4 of the drawings, illustrating the mechanism for actuating the type bar and disclosing the connections between the controlling magnets, the battery and the contacts for the finger keys.

Fig. 7 is a top plan view of the means for imparting step by step movement to the platen roll.

Referring to the several sheets of drawings and more particularly to Figs. 1 and 2 thereof, the numeral 1, is used to designate the main frame or casing of the typewriter, which houses and supports the various internal working parts of the apparatus 90 and the means for throwing into action the electrically controlled mechanism of the machine. Within the keyboard portion of the machine is mounted for free vertical movement the depressible spring held finger keys 95 2, which keys are mounted in the ordinary manner common to typewriters of standard make. The spacing bar for controlling the rotatable movement of the platen is designated by the numeral 3, and the finger keys 100 100 for raising the platen to position the same to receive the imprint of capital letters and the numerals of the typewriter are designated by the numeral 4, while the keys for controlling the ordinary tabulating mechanism of the typewriter are represented by the numerals 5, but such tabulating mechanism forms no part of the present invention.

Within the frame of the machine is located a series of coiled magnets 7, there being a pair of such magnets for each of the 110

finger keys 2 of the apparatus, as will be seen by reference to Figs. 1, 2, and 6 of the drawings, and inasmuch as the said finger keys and their associated parts are duplicates, the description of one will suffice for the others. For each pair of magnets 7 there is provided a pivoted armature 8, which said armature is thrown into action by the said coiled magnets 7 when energized 10 on the closing of the finger keys' contacts. The said armature, Figs. 3 and 6 of the drawings, is pivotally mounted at its inner end on an axle or rod 12 extended throughout the length of the machine and which 15 serves as a common axle or supporting rod for the armatures 8, each armature being separated one from the other by means of suitable washers, not shown on the drawings. The inner end of each of said armatures when in lowered position bears or 20 rests on and is supported by a projection or extension 9' of a toothed oscillator 9, Figs. 1, 3 and 6 of the drawings, there being an oscillator for each armature 8, which 25 said oscillators are mounted for free swinging movement on an axle or supporting rod 11, held within the frame of the machine and extending throughout the length thereof and which serves as a common sup- 30 porting rod or shaft for the series of swinging oscillators 9, which like the armatures 8, are separated one from the other by means of washers placed on the rod or shaft 11. These oscillators 9, are free to swing 35 through the action of the armature 8, when the armature is drawn downwardly on the energizing of the magnets 7, the free end thereof at such times exerting a downward pressure on the extension 9' of the oscillator 9 and by the pressure exerted thereon 40 throwing the same forwardly relative to the axle or supporting shaft 11. The weight of each swinging oscillator is so proportioned relative to its pivotal axis, so as to cause 45 the same to normally stand inwardly thrown, when the armature 8 is away from the magnets 7. Each swinging oscillator 9 is provided with a tooth or gear section 9^a, which meshes with the tooth or rack section 50 10' of a type bar 10, which type bars are pivotally mounted at their inner end on an axle or supporting rod 12', which is secured within the frame of the machine and extended within the length thereof and serves 55 as a common support for each of the type bars 10. Each type bar 10 at its outer end carries a type head 12^a, which, when the bar 10 is in lowered position as illustrated by Figs. 3 and 6 of the drawings, rests on and 60 is supported by an inwardly extended bracket portion 1^a, of the front wall portion of the frame 1.

The supporting shafts or axles 11 and 12' are held within ears 14 and 14' of a sup- 65 porting bracket 14^a, Fig. 3 of the drawings,

supported by the member 14^a it being understood that there is provided a supporting bracket 14^a for each end of the rods or axles 11 and 12', the said brackets 14^a being suitably held to the inner side wall 70 of the frame 1 of the machine, while the shaft or axle 12 for the armatures 8 is held or mounted at each end within brackets 15.

The levers 16 for controlling the lift mechanism for the platen roll are actuated 75 by either of the finger keys 4, said levers being pivoted at substantially the center thereof on the shaft 16^a, Fig. 3 of the drawings, and constituting a pivoted frame which is thrown into action by the movement of either of the keys 4, when it is desired to raise the inner end portion thereof to lift the platen roll to position the same to receive an imprint from the capital letter sections of the type head of the type 80 bars 10. On the inner portion of the said pivoted frame rests the lower portion of a vertically disposed portion 17 of a rectangular frame, the end walls of which frame are slotted as shown at 17^a, and 85 through which slotted portions are extended the pins 17^b for holding the same to the inner side wall of the frame of the machine. The upper or grooved longitudinally disposed piece 17^a of the said vertically movable frame 17 constitutes a guide rail on which is longitudinally movable the frame 18, which supports the platen 19, which said roll at one end carries a toothed 90 wheel 20, the purpose of which is to impart 95 step by step rotation to the said platen when the carriage is returned to starting position said wheel being actuated by a dog 21 fulcrumed as at 22, Fig. 3 of the drawings.

To the ears 23 of the frame 18, Fig. 3 of the 100 drawings are pivotally connected the ends of members 24 which project beyond the platen roll 19 and are connected by means of a longitudinal shaft 25, on which are mounted the usual paper pressure rolls 26, the said end 105 members of the frame 18 being pivotally connected at their inner end as at 29 to the carriage 30, which said carriage is longitudinally slidable on the main frame 1, as is usual in the ordinary typewriter construction, and the same is operated to move longitudinally by a toothed wheel 34, which engages the rack teeth 31 formed on the end of the depending rear wall portion of the carriage 30. The pressure rolls rest on the 110 upper surface of the platen 19 and retain the upwardly extending portion of the paper in contact with the platen. The portion of the paper lying adjacent the under surface of the platen is held in contact therewith by 115 other pressure rolls 27 carried on a rod 27^a supported at its ends by the fulcrumed arms 27^b, the rolls being held in contact with the paper by springs 27^c. The shaft carrying the tooth wheel 34, Figs. 4 and 6 of the 120 125 130 drawings,

- drawings is rigidly attached by a collar 33^a to a dog tooth gear 33, which gear is actuated by a pawl 34' carried at the free end of the armature 35 fulcrumed as at 47 and the free end of which is normally raised by the spring 45^a, the action of which armature is controlled by the energizing of the coiled magnets 36. On the collar 33^a connecting the gear 33 to the gear 32, is a coiled spring 37, the free end of which is attached to the frame of the machine as shown in Fig. 4 of the drawings, and the purpose of said coiled spring is to cause a reverse movement to the carriage on the release of the gear 33.
- 15 On the platen roll reaching the end of its line of travel during the operation of the machine, it is required that the same be automatically restored to normal position. For this purpose, there is provided at one 20 end of the carriage a projecting inclined stud 39, which engages with and rides on the upwardly inclined surface 40, of a trip lever 41, pivoted within its length to the frame of the machine, and with its inner end 25 connected therewith by the spring 42. This trip lever 41, is provided with a downwardly projected dog 43, which is normally in engagement with the teeth of the gear 33. However, as the lug 39 rides over the inclined section 40 of the lever 41, the free end 30 of said lever is depressed or swung downwardly, throwing outwardly the dog 43, and placing the same out of engagement with the teeth of the gear 33 and thus releases the 35 said gear. When thus released, there takes place an unwinding action of the spring 37, which imparts a rapid reverse rotation or movement to the gear 33, and its associated gear 34 causing the latter gear to return the 40 carriage with the platen roll to its normal or starting position.
- Each finger key 2 of the machine is connected by the wires *a* and *a'* to the battery 44 and to the battery 45 respectively controlling the magnets 36 and 7, the wire *a'* leading from the contact point 2^b carried by each key 2, Fig. 6 of the drawings. On the downward movement of any of the keys 2, 45 the contact 2^b carried thereby is first brought into contact with the contact plate 2^c, which contact is connected by the wire *c* through the magnet coils 36 with the battery 44, so that when the contact between the points 2^b and 2^c is made the circuit is closed through 50 the battery 44 to the magnets 36, which actuates the armature 35 and its described associated parts 34', 33 and 34 and 31 to advance the platen roll one space. On the continued downward movement of any one of 55 the keys 2, the contact 2^c is depressed until contact is made with the contact 2^d, which is connected by the wire *d* to the magnets 7 and the battery 45, so that when this circuit is closed the magnets 7 are energized to 60 actuate the armature 8 for throwing the oscillator 9 to raise the type bar 10 for making an imprint of the letter or number carried by the head 12^a onto the platen roll of the machine. Thus, with each depression of any of the finger keys 2, the action is to 65 first energize the magnets 36, to operate the armature 35 and its associated parts to advance the platen roll one space, and secondly, to close the circuit to energize the magnets 7, and thereby actuate the armature 70 75 80 85 90 95 100 105 110 115 120 125 130
- 8 to throw the type bar 10 to make an imprint on the platen roll. There are no electrical circuits established by the depression of the finger keys, 4, 5, or 6, but, on the depression of the spacing bar 3, there is a closing of the contact 3^a and 3^b, which closes the circuits through the wires 4^a and 4^b to the magnet 36 and battery 44, energizing the magnets 36 to operate the armature 35 to actuate the gears 33 and 34 for advancing the platen frame one space or more in accordance with the number of times in which the spacing bar is actuated.
- It will be observed from the foregoing description that the actuating mechanism for the typewriter is of such construction as to produce substantially a silent operated machine and one wherein but slight pressure is required on the finger keys for throwing into action the type bars.
- It will be understood that there is a pair of magnet coils 7 for each of the finger operating keys 2, and that for each key there are two controlled contacts and that a movement of any of said keys first throws 100 into action the electrically controlled spacing mechanism for the platen roll and at a subsequent period of time the electrically controlled means for actuating the type bar.
- While the invention has been described in its preferred embodiment I do not wish to be understood as limiting or confining myself to the detailed construction of the working parts herein shown and described, 110 but wish to cover the invention as broadly as the state of the art will permit.
- Having thus described my invention what I claim as new and desire to be protected by Letters Patent is:
1. In a typewriter, the combination with the carriage thereof, of a series of pivoted type-bars, a depressible finger key for each type-bar, independently controlled electrically operated means common to all of said 120 keys for advancing the carriage one space on one portion of the depressed movement of a finger key, and independently electrically controlled means for each type-bar, said means thrown into action on the continued depressed movement of said finger key.
  2. The combination with a typewriter, of a series of pivoted type-bars, a series of independently controlled electrically operated 130

means situated within the frame of the machine, one for each of the type-bars, a depressible finger key associated with each type-bar, a contact carried by each of said keys for closing the circuit controlling the operation of the electrical means for actuating the type-bar associated with the finger key on a depressing thereof, and electrically controlled means common to all of the depressible finger keys for advancing the carriage of the machine on the initial depressing movement of any of the finger keys for actuating a type-bar.

3. The combination with a typewriter, of independently controlled electrically operated means within the frame of the machine for advancing the carriage one letter space and actuating the type-bars of the machine, a depressible finger key for the type-bar of the machine, and contacts associated with each key and successively closed on the depressed movement of any key to first close the circuit controlling the action of the electrically operated means for advancing the carriage one letter space and secondly to

close the circuit controlling action of the electrically operated means for operating the type-bar associated therewith.

4. In a typewriter, the combination with the shifttable carriage thereof, of a plurality of pivotally mounted electrically actuated type-bars, electrically operated spacing means for advancing the carriage a letter space, a depressible finger key associated with each type-bar, and a plurality of circuit controlling means associated with each finger key and successively operated by the depressing of a key to first close the circuit for actuating the electrically controlled spacing means and secondly to close a circuit to actuate the electrically controlled means for operating the type-bar associated with such depressed finger key.

In testimony whereof I have signed my name to this specification in the presence of a subscribing witness.

WM. F. SMITH.

Witness:

D. B. RICHARDS.
